PATENTED APR. 14, 1908.

E. E. KLEINSCHMIDT.
SIGNALING SYSTEM.
APPLICATION FILED SEPT. 1, 1906.

UNITED STATES PATENT OFFICE.

EDWARD E. KLEINSCHMIDT, OF NEW YORK, N. Y., ASSIGNOR TO GEORGE M. SEELEY, OF NEW YORK, N. Y.

SIGNALING SYSTEM.

No. 884,738.

Specification of Letters Patent.

Patented April 14, 1908.

Application filed September 1, 1906. Serial No. 332,972.

To all whom it may concern:

Be it known that I, EDWARD E. KLEINSCHMIDT, a citizen of the United States, residing at the city of New York, in the county 5 of New York and State of New York, have invented certain new and useful Improvements in Signaling Systems, of which the following is a specification.

In my application Serial Number 304,610, 10 filed March 7, 1906, is described a signaling system in which the signal circuits are on the normal danger principle so that through failure of the line or power circuits, or breaking of either line or local connections, the signals 15 will be instantly set at danger and cannot be cleared until the disturbing cause has been corrected. In that system the selective signal switches are governed by a controller at the home office so as to be both set and cleared 20 by the despatcher. Miniature signals moved in synchronism with the track signals are provided to advise the despatcher of the setting and clearing of the latter signals.

In the present system the selective signal 25 switches are included in a single line circuit and are only set by the controller at the despatcher's office instead of being both set and cleared as in the system of my previous application. When a given signal is set the 30 motorman receives his instructions by telephone and manually clears the signal when told to do so, provision being made to advise the despatcher by a visual or audible signal when the track signal has been cleared. The 35 track signals are held at normal or safety position by normally energized electromagnets included in the line circuit, a shunt circuit being closed around a given magnet by the corresponding selective switch to thereby 40 deenergize said magnet to effect the setting of the signal.

The present system also includes means for synchronizing the selective switches and other features which will be fully described 45 hereinafter.

The invention will be understood by reference to the accompanying drawings in which

Figure 1 is a diagrammatic view of the 50 system; Fig. 2 a detail view of the means included in the line circuit for operating a signal at the despatcher's office to indicate the setting and clearing of the track signals; Fig. 3 a plan view of a part of one of the sig-

nal selective switches; and Fig. 4 a vertical 55 section on the plane of the line 4—4 of Fig. 3.

Similar reference numerals indicate similar parts in the several views.

Referring to the drawings the numeral 1 designates the main line and 2 the sidings of 60 a single track road, although it is to be understood that the present system is also adapted to a double track road. Any number of signals may be included in the system they being located on a single track road in 65 proximity to the sidings so as to be readily observed by the engineer or motorman. The signals may be of any standard type and as they are set and cleared by similar means it will only be necessary to refer to one of the 70 switches in detail. Two signals are shown in the drawings and they will for convenience be referred to as stations A and B respectively. In the system illustrated the semaphore blade 3 is held in normal or safety position by an electromagnet 4 included in a single line circuit 5, the specific mechanism illustrated comprising an armature 6 in the form of a bell crank lever which being normally held in its attracted position bears 80 against a locking lever 7 adapted to engage a notch on the blade 3 to hold the latter in the position stated. The holding magnets 4 are normally energized by current from the line circuit and each of said magnets is included 85 in a normally open shunt circuit 8 so that when the latter is closed the corresponding magnet will be deenergized to permit the withdrawal of latch lever 7 by a spring 9. When that occurs the weighted spectacle end 90 of the blade will set the latter at danger in which position it will remain until manually cleared by the motorman through the downward movement of a rod 10, the latter having a handle within convenient reach. 95

In order to deenergize the magnets 4 by closing the corresponding shunt circuit 8 I provide selective switches which are adjusted according to the number of the track signal so as to prevent interference of one 100 switch with another, the setting of the switches being governed by a controller at the despatcher's office as will now be described.

Located at the home or despatcher's office 105 is a switch board 11 having thereon switches corresponding in number to the track signals, the purpose being that the despatcher shall

only set and not clear the signals. Each of the switches comprises a lever 12 retained in normal position by a spring 13, and a contact plate 14. These switches, as shown in Fig. 1, are adapted to close local circuits through a controller which structurally is the same as in my application Serial Number 304,610 the circuits only being modified to meet the changed conditions of the present system. 5 It is sufficient for present purposes to state that this controller comprises a series of electromagnets, one magnet for each selective switch. As shown there are five magnets designated 15, 15', 15'', etc., each of which 10 controls a given switch, and a magnet 16 in circuit with each of the other individual magnets. All of the controller magnets are connected to a common return wire 17 and their circuits derive current from any suitable 15 source as 18. The switches and magnets of the controller will be suitably designated to correspond with the track signals controlled thereby.

The armatures 19, 19', 19'', etc., of the 20 magnets 15, 15', 15'', etc., and armature 20 of magnet 16 are pivoted on brackets 21 and normally held in a retracted position in such relation to each other that armatures 19, 19', etc., bear against an insulated ring 22, and armature 20 against a stop pin below the 25 plane of armatures 19, 19', etc.

The initial operation of this controller is to release a commutator for the purpose of alternating the normal direct current on the single 30 line circuit 5 which is connected to a suitable source of energy as 23, such alternating current being utilized to effect a step-by-step movement of a ratchet wheel included in the selective signal switch. To accomplish this 35 I provide commutator 24 against which rest brushes 25 and 26 arranged in pairs and included in the line circuit, such construction being one well understood. On the shaft of commutator 24 is keyed a pinion 27 which 40 meshes with a gear wheel 28, said shaft being connected with any suitable driving means which will effect its rotation when the commutator is released. Gear 28 is keyed to a vertical spindle 29 on which is fixed an arm 45 30, said arm normally resting against the projecting end of armature 20 so that the latter acts as a stop therefor to hold the commutator at rest.

Assuming that the signal designated A is 50 to be set the despatcher moves the first switch lever 12 on to its contact plate 14 thus closing the controller circuits through magnets 55 15 and 16. Armature 20 will thus be attracted so as to release arm 30, and armature 19 will be attracted so as to lie across the path 60 of travel of said arm when it is rotated. The release of arm 30 will permit of the rotation of commutator 24 and spindle 29 such rotation continuing until arm 30 is brought to 65 rest by engaging armature 19. During the

rotation of the commutator the direct current on line circuit 5 will be converted into an alternating current as will be readily understood and this latter current is utilized as follows.

The signal selective switches are similar in construction and comprise an electromagnet 31 included in the line circuit 5 and normally energized so as to hold its pivoted armature 32 in its attracted position. Said armature 75 carries an insulated section as shown in Fig. 1 to which are attached normally separated spring contacts 33, said contacts constituting terminals of shunt circuit 8. Also included in line circuit 5 is a polarized magnet 34 between the poles of which is a pivoted lever 35. This lever carries at its outer end an actuating pawl 36 which engages the teeth of a ratchet wheel 37 said wheel being keyed to a shaft 38 stepped into the arms of a bracket 80 39. Adjustably secured to said shaft is a projecting stop arm 40 which will be carried around when ratchet 37 is rotated. Owing to the high self-induction of magnet 31 it 85 will be deenergized during the alternations of the current on line circuit 5 and armature 32 with the spring contacts 33 carried thereby will be retracted at such time by a spring 41, and during the same period ratchet wheel 37 will be stepped around by the alternate attraction and repulsion of lever 35 of polarized magnet 34. The length of travel of the controller arm 30 between its normal position of rest against armature 19 is such that arm 40 of ratchet 37 of the corresponding selective 90 switch will be stepped around a sufficient distance to be brought directly back of the inner spring contact 33. When arm 30 is brought to rest against armature 19 the line circuit 5 will be restored to normal condition thereby 95 energizing magnet 31 and attracting its armature 32. As the latter moves to its attracted position contacts 33 will be pressed together by reason of the impingement of the inner contact against arm 40 thus closing 100 shunt circuit 8 and deenergizing the holding magnet 4. When the locking lever 7 is so released blade 3 of signal A will move to danger position.

Through telephone 42 the motorman receives his instructions from the despatcher and when advised to clear the signal he does so by pulling downwardly on rod 10. In the meantime the despatcher by releasing switch lever 12 opens the circuits of magnets 15 and 16 and when these are deenergized their armatures 19 and 20 respectively will resume 115 their normal positions, the former freeing arm 30 which is then rotated in the direction of the arrow until brought to rest in its 120 normal position against armature 20. During this period of rotation of commutator 24 the current on line circuit 5 will be converted into an alternating current thereby causing 125 the above described movement of lever 35 of 130

- the polarized magnet 34 to actuate ratchet 37 to restore arm 40 to normal position. Upon the removal of arm 40 from the position in which it was placed to effect the closing of shunt circuit 8, the spring contacts 33 will separate thus opening said circuit. At the same time magnet 31 will be deenergized to permit its armature 32 to be retracted. When arm 30 is brought to normal position 10 against armature 20 the rotation of commutator 24 will be arrested and normal conditions being again restored on line circuit 5 the magnets 4 and 31 will be energized, the former moving lever 7 into position to engage 15 blade 3 when the motorman manually clears the signal. The parts are now in normal positions ready to be operated as above described when the signal of station A is to be again set.
- 20 All of the selective signal switches are grouped in series and included in line circuit 5 so that when arm 30 is released by the movement of any one of the switch board levers the magnets 31 of all of the selective 25 switches will be deenergized, and the levers 35 of all of the switches will be vibrated. When the magnet of the controller corresponding to a signal that is to be set arrests the movement of arm 30 then the magnets 31 30 of all of the switches will be energized and the ratchets 37 of all of the switches will be brought to rest, but the arm 40 of the switch corresponding to the signal to be set will be the only one in position to effect the closing 35 of a shunt circuit 8. In order to avoid interference in the setting of the signals it is necessary that the selective switches shall be so timed relatively to each other that when an arm 40 of one of the switches is in position 40 to close a corresponding shunt circuit 8 no other arm 40 will be in position to close its corresponding shunt circuit. This is accomplished by adjusting the arms 40 of the several switches in such manner that one will 45 be in advance of the other, this adjustment being in harmony with the position of the several magnets of the controller. From the above description it will be observed that magnet 15 controls the setting of signal A; 50 magnet 15' that of signal B; magnet 15² that of signal C and so on around the controller. These magnets and magnet 16 are so disposed 55 in the controller that the projecting ends of their armatures are equidistant so that the same number of alternations of the current on line circuit 5 are obtained when arm 30 passes from one armature to the next succeeding. This will always result in positioning a given arm 40 of one of the selective 60 switches according to the position of arm 30 against a controller magnet.
- For the purpose of advising the despatcher 65 through an audible signal that a given track signal has been set or cleared according to his intention, and for making a permanent
- record of the fact I secure a rack 43 to the lower end of rod 10 so as to be moved thereby in both directions. A brush 44 rests against said rack and both are included in line circuit 5, said circuit being closed when 70 these parts are in the position indicated in the drawings. When signal A is set in the manner before described the rack 43 will be drawn upwardly and wiping past brush 44 will alternately open and close line circuit 5 75 to ring a bell 45 included in said circuit. This bell will also be rung when the signal is cleared; and in order that the despatcher may be advised thereby whether the signal has been set or cleared the rack 43 is so constructed as to ring the bell 45 a given number 80 of times for a movement of said rack in one direction, and a greater or less number of times for a movement in the opposite direction. This may be effected by pivoting a 85 cover plate 46 on the side of the rack in such position that as the rack moves upwardly said plate will be moved by contact thereof with brush 44 so as to bridge the first space in rack 43. Thus in the rack illustrated the 90 bell 44 will be rung five times when the signal is set which number will be that of the station. As soon as cover plate 45 passes brush 43 said plate will resume its normal 95 position as indicated so that when the signal is cleared bell 44 will be rung six times which may be the signal agreed upon for the clearing of station number 5. Also included in line circuit 5 is any ordinary type of recorder 47 which when operated by the movement of rack 43 as just described will make a permanent record on the tape 48 of the signal which has been set or cleared. By this means the despatcher is advised that the proper signal has been set or cleared and in 100 case of dispute the record made by the recording instrument 47 will determine the fact.
- When line circuit 5 is broken by rack 43 passing downwardly past brush 44, a resistance 49 is interposed in the circuit which does not reduce the strength of the current 110 sufficiently to deenergize the holding magnet 4, but such current is sufficient to effect the ringing of the bell and the operation of the 115 recorder as above described.
- In the present system is also included a series of miniature signals which may be conveniently placed on the switch board 11 at the despatcher's office and adapted to be set 120 in synchronism with the track signals either through the local controller circuits alone or through said circuits in connection with line circuit 5. These miniature signals serve as an indication to the despatcher that the 125 proper track signal has been set. They comprise a blade 50 connected to the core of a solenoid 51 the latter being included in the corresponding controller magnet circuit so that when said circuit is closed to set the 130

4
track signal solenoid 51 will be energized and its core drawn inwardly to set the signal. When the controller magnet circuit is opened through switch lever 12 the despatcher 5 manually restores the miniature signal to safety position.

In order to set the miniature signals through line circuit 5 I interpose in said line circuit, preferably at the despatcher's office, 10 a relay 52 the armature of which is normally attracted. According to this latter method when the despatcher moves switch lever 12 on to contact plate 14 then solenoid 51 will not be energized, but by retaining said lever 15 on its plate and breaking the line circuit 5 through the movement of rack 43 then relay 52 will be deenergized thereby permitting its armature 53 to be retracted by a spring to engage the contact 54 included in return 20 circuit of solenoid 51. When said return circuit is closed solenoid 51 will be energized to set its signal. In this connection it will be noted that the holding magnet 4 should be made slower acting than relay magnet 52. 25 It is essential in a system comprising selective signal switches that means be employed to synchronize said switches. The mechanism for accomplishing this is substantially the same as described in my application Serial Number 304,610. As shown 30 in Figs. 3 and 4 the armature 32 of magnet 31 has secured thereto a bracket 55 on which is pivotally mounted an arm 56. In an opening in the end of said arm is loosely 35 mounted a follower 57. Said follower is held in said opening by a spring 58. The follower 57 engages a groove 59 on ratchet shaft 38. During the normal operation of the system when magnet 31 is energized 40 the arm 56 is moved backward so as to release follower 57 from the cam groove. During the alternations of the current on line circuit 5 and when magnet 31 is deenergized the follower 57 moves into engagement with 45 said groove and when ratchet 37 is fed the arm 56 will be carried downward and released only when magnet 31 is again energized. Under normal conditions arm 56 is never moved to its lowermost position, said 50 arm being restored to its uppermost position by the action of a spring 60 when magnet 31 is energized. In order to insure that the arms 40 of the selective switches are in proper adjustment I provide a switch 61 in 55 the circuit of magnet 16. When switch 61 is closed said magnet will be energized thus releasing arm 30 and permitting it to rotate as long as the switch is closed. This as 60 above explained, results in deenergizing magnet 31 and permitting follower 57 to remain in engagement with cam groove 59, and ratchet 37 to be fed until arm 56 is carried to its lowermost position. When that occurs a stop pin 62 on the face of ratchet 37

will contact with toe 63 on arm 56 thereby 65 arresting the movement of ratchet 37. Stop pin 61 is so placed that when this contact takes place the arm 40 will be in normal position. It will be understood that stop pin 61 is differently positioned in the several 70 selective switches.

The commutator 24 may be divided into a sufficient number of sections to secure the rotation of ratchet wheel 37 at least once when switch lever 12 is moved from its contact 75 14 after the setting of the signal. This will always insure the proper adjustment of the arms 40.

It will be noted that while a direct current is impressed upon line circuit 5 the step-by-step mechanism of the selective switches is at rest. When the current is alternated by the commutator 24 a change takes place in 80 said circuit. Starting from minimum the current strength increases to maximum effecting the movement of lever 35 of the polarized magnet 34 in one direction, and in an opposite direction upon the reversal of the current. The selective signal controlling 85 switches are, therefore, moved step-by-step 90 in response to the fluctuations in the current of line circuit 5.

It will be observed that by reason of the inclusion of the signals in a single line circuit 95 it is evident that if said circuit is broken so as to prevent the despatcher from operating the system all of the signals will instantly move to danger because of the holding magnets 4 being deenergized. By the employment of a single line circuit which includes 100 the commutator, the selective signal switches and the holding magnets the system is greatly simplified and requires less attention and repairs, and lessens the liability of derangement. 105

To enable the despatcher in event of an emergency to set all of the track signals simultaneously I include in line circuit 5 a switch 64. When said switch is opened all of the signal holding magnets 4 will be deenergized thus permitting the signals to move to danger position as before explained. 110

What I claim and desire to secure by Letters Patent of the United States is:—

1. In a system of the character described, 115 a plurality of signals normally held at safety and adapted when released to automatically move to danger position, electromagnets adapted to hold the signals at normal position, a single line circuit in which said magnets are included, and means for deenergizing a given magnet to set the corresponding signal. 120

2. In a system of the character described, 125 a plurality of signals, normally energized electromagnets adapted to hold said signals at safety position, said magnets being connected in series in a single line circuit, and

- means for deenergizing a given magnet to permit the corresponding signal to move to danger position.
3. In a system of the character described, 5 a plurality of signals, normally energized electromagnets adapted to hold said signals at safety position, a single line circuit in which said magnets are included, selective signal switches, and means for actuating said switches to deenergize a given holding magnet to thereby set the corresponding signal.
4. In a system of the character described, 10 a plurality of signals, normally energized electromagnets adapted to hold said signals at safety position, selective signal switches, a single line circuit in which said magnets and switches are included, and means for actuating a given switch to effect the setting of the corresponding signal.
- 15 5. In a system of the character described, a plurality of track signals, normally energized electromagnets adapted to hold said signals at safety position, selective signal switches adapted when operated by an alternating current to set the signals, a single line circuit in which said magnets and switches are included, and means for impressing upon said circuit a current of a predetermined number of alternations.
- 20 6. In a system of the character described, a plurality of track signals, normally energized electromagnets adapted to hold said signals at safety position, selective signal switches adapted when operated by an alternating current to set the signals, a single line circuit in which said magnets and switches are included said circuit normally carrying a direct current, and means for converting said direct current into an alternating current for 25 the purpose of operating said switches.
- 30 7. In a system of the character described, a plurality of track signals, normally energized electromagnets adapted to hold said signals at safety position, selective signal switches, a single line circuit in which said magnets and switches are included, a controller having a series of adjustable stops corresponding to the track signals, and means for setting a given stop to operate the 35 corresponding signal switch.
- 40 8. In a system of the character described, a plurality of track signals, normally energized electromagnets adapted to hold said signals at safety position, selective signal switches adapted when operated by an alternating current to set the signals, a single line circuit in which said magnets and switches are included said circuit normally carrying a direct current, a controller comprising a 45 commutator also included in said circuit, and means to actuate said commutator to convert the direct current into an alternating current to effect the operation of a given switch to set the corresponding signal.
- 50 9. In a system of the character described, 55 a plurality of track signals, normally energized electromagnets adapted to hold said signals at safety position, selective signal switches, a single line circuit in which said magnets and switches are included, said circuit normally carrying a direct current, and means to actuate said commutator to convert the direct current into an alternating current to effect the operation of a given switch to set the corresponding signal.
- 55 10. In a system of the character described, 60 a plurality of track signals, normally energized electromagnets adapted to hold said signals at safety position, a single line circuit in which said magnets are included said circuit normally carrying a direct current, means for alternating said current, and mechanism adapted to be set when the current is alternated to effect the deenergizing of a given magnet to release the corresponding signal.
- 65 11. In a system of the character described, 65 a plurality of track signals, normally energized electromagnets adapted to hold said signals at safety position, selective signal switches, a single line circuit in which said magnets and switches are included, a shunt circuit for each of said magnets, and means to close a given shunt circuit to thereby deenergize the corresponding signal holding magnet.
- 70 12. In a system of the character described, 70 a plurality of track signals, normally energized electromagnets adapted to hold said signals at safety position, a shunt circuit for each of said magnets, selective signal switches, and a single line circuit in which 75 said magnets and switches are included, said switches comprising means responsive only to fluctuations in the current of the line circuit to effect the closing of said shunt circuit to thereby deenergize the corresponding signal holding magnet.
- 75 13. In a system of the character described, 80 a plurality of track signals, normally energized electromagnets adapted to hold said signals at safety position, selective signal switches, a single line circuit in which 85 said magnets and switches are included, said selective switches comprising a polarized magnet, a ratchet wheel adapted to be actuated by said polarized magnet, and means 90 set by a given ratchet wheel to effect the deenergizing of the corresponding signal holding magnet.
- 80 14. In a system of the character described, 95 a plurality of track signals, normally energized electromagnets adapted to hold said signals at safety position, selective signal switches, a single line circuit in which 100 said magnets and switches are included, said switches comprising a polarized magnet, a ratchet wheel and actuating pawl therefor, a pawl-carrying lever adapted to be vibrated by said polarized magnet, and means for 105 alternating the current on said line circuit to effect a step-by-step movement of said 110

ratchet wheel through said polarized magnet for the purpose described.

15. In a system of the character described, a plurality of track signals, normally energized electromagnets adapted to hold said signals in safety position, selective signal switches, a single line circuit in which said magnets and switches are included, and means for synchronizing said switches.

10 16. In a system of the character described, a plurality of track signals, normally energized electromagnets adapted to hold said signals in safety position, selective signal switches, a single line circuit in which said 15 magnets and switches are included, and telephones bridged in the line circuit at the signal stations.

17. In a system of the character described, a plurality of track signals, normally energized electromagnets adapted to hold said signals in safety position, selective signal switches, a single line circuit in which said magnets and switches are included, miniature signals at the home office, and means 25 for setting said miniature signals in synchronism with the track signals.

18. In a system of the character described, a plurality of track signals, means for setting and clearing said signals, a circuit including an indicator, and means connected to the signals for operating said indicator a given number of times when a given signal is moved in one direction, and a greater or less number of times when the signal is moved in the opposite direction. 30

19. In a system of the character described, a plurality of track signals, means for setting and clearing said signals, a circuit including a bell, and means connected to the signals to effect the ringing of said bell a given number of times when a given signal is moved in one direction, and a greater or less number of times when the signal is moved in the opposite direction. 40

In testimony whereof I have hereunto signed my name in the presence of two subscribing witnesses.
